Conrad Kile Eric Penn.
Letters Patent

The Schedule referred to in these Letters Patent and making part of the same containing a description in the words of the said Conrad Kile himself of his improvement in constructing beams for bearing the load for making stocks.

To all to whom these presents shall come Be it known that I, Conrad Kile of Erie in the County of Erie in the State of Pennsylvania have invented a new and useful improvement in the Beam for bearing Stocks and that the following is a full and exact description of the construction of the construction and operation of the said machine as invented or improved by me The frame work may be made after the usual practice of putting together beams But as the beam upon which the hoop is wound; also that upon which the stock is wound, and that in which it is strained all in their usual vibrations but my improvement consists in the form or mode of constructing them and is grammatical in the following respects to make the stock set closely the neck and accommodate itself to the shape; viz that the stock should be made longer than the centre of the cloister so that while the centre of the stock fits the neck closely the cloister both at top and bottom is to be made as wide easily to the passage of the cloister after the manner generally effected by inserting pieces of an angular shape around the top and bottom. The object of increasing the length of the cloister is by means of the shape I give the beams above mentioned on their circumference for instead of their being straight across from end to end I form them with a concave circumference so proportioned that the girth of the centre of the beam is about one third less than that of each end and succeeds in a gradual state till it arrives at its full height on each end thereof. This causes the beam to assume a semi-circular shape and as more strength is required towards the cloister in order to support and cause the stock to remain in shape they are warped on the beam from bottom to top by which warping the number may be increased towards the cloister at pleasure. In order to prevent the warping from slipping down as it rises up the side of the concave place

a number of pins rising perpendicular from the surface of each wheel. It is not to interrupt the running of the warp, upon or off the beam; A ratchet wheel and band is applied theron as usual; the pins through which the ends of the warp are passed are brought into the requisite semi-circular shape by means of the tool on the top, having their upper side cut into the same concave as the beam; and the bottom of the lever bar cut into a convex of the same proportions which brings the loops of the straight warp into the requisite form; the ends of the warp are brought over the straining beam in front and connects the cloth beam beneath this said straining beam which has such a portion of its under surface decapitated as to admit the cloth beam to fit or work in this hollowed place; the latter being about one half the circumference of the former (through the length side to the others) and consequently the concavity of the latter will be in the same proportion, say one half & when other proportion may be used. The cloth beam is also sufficiently in the front of the latter to make the straining beam to bring the line of concavity of the former to correspond as nearly as possible with that of the latter so that the cloth has no hindrance in passing from one to the other in the same semi-circular shape and the straining beam is allowed to be loose upon its axis so that as the cloth beam fills up it continues to press against the open part of the hollow and consequently causes the former to recede and leave room for the accumulation of the clothed band and ratchet wheel and adopting the cloth beam as usual, I construct, say, and incorporate in a different manner, from the common principle it being necessary to admit it to the concavity of the beam. This I effect by giving to the lever bar into which the ends (or rather their strips of steel such as blocks, springs) are secured, the same semi-circular shape as the straining beam, so as to fit the air circumference exactly and it must also be brought into a sharp edge, & find that much abiding this purpose better than wood and on the upper or sharp edge side are cut for the reception of the metal plate which when placed over it of course assumes the curved shape of the metal plate and exactly fit the bottom of the beam. They are then soldered and secured. The upper or top bar is made straight as usual and if of wood it must either have a metal plate (through the rest a sharp edge) into the side of

While the ends of the stalks are retained and secured, uprights at each end either of metal or wood are used to support the ends of the top & bottom plates so as to keep them steady and by means of a Martin and Sonnen with a blunt screw these plates may be released, and the end changed for another, the mode of operating my web being different from the German method. I connect to the bottom of each upright an arm in the same place but in an obtuse angle through hot metal, where there is a right angle which is to be sufficiently long to reach to the edge of the straining beam on which it is secured so as to allow or reduce on said axis one arm being projected outwards and is to be sufficiently long just to bring the sharp edge of the web close upon the circumference of the concavity, consequently because of this the motion given to the web to receive at a regular distance around the said beam. The arrangement of the needles here is the same as other looms which are to be more or less according to the pattern intended to be produced which can be varied in this loom as well as any other by operating the warp is produced by the motion of the needles and by means of a small shuttle one shot is made to pass through a thread either of Cotton or silk then a bristle is placed and then another shot made and so on to suit the intention of the weaver. I prefer using the thread for the purpose of preventing the bristles from slipping out. Then it will be seen that at each end of the web the sharp edge brings the bristles straight by the side of each other in the place of a section through the diameter by which means they are not strained out of a straight line or straight by the side of each other otherwise than according to the curve of the beam. I have the increased quantity of warp prevents the possibility of them in falling out again. I propose to contract my looms to work not only tightly but correctly as power looms do. The quantity of chain is increased as much as to have a good selvage with full up & down of the span between the needles as will be requisite to give the cloth a uniform clean appearance. What I claim as my invention is the above described machine and not previously known is the concave shape I give to all my beams & to the web and secondly the manner of stretching the loom from the center to the ends, lastly the manner of joining the uprights of the web by means of

I swear to the accuracy of the foregoing claims as already described & to the intent
of testifying that the above is a full, clear, and exact description of the construction
and operation of the said machine as invented or improved by me I
here subscribe. Set my hand this thirteenth day of July eighteen hundred
and thirty five.
